UNITED STATES PATENT OFFICE.

LINNAEUS E. BAKER, OF FORT WAYNE, INDIANA, ASSIGNOR TO WAYNE OIL TANK AND PUMP CO., A CORPORATION OF INDIANA.

METER.

1,278,825.

Specification of Letters Patent. Patented Sept. 17, 1918.

Application filed October 26, 1915. Serial No. 57,940.

To all whom it may concern:

Be it known that I, LINNAEUS E. BAKER, a citizen of the United States of America, and resident of Fort Wayne, in the county 5 of Allen and State of Indiana, have invented certain new and useful Improvements in Meters, of which the following is a specification.

This invention relates to improvements in 10 counting apparatus for liquid dispensing pumps of that class ordinarily employed in retailing gasoline and oils, and is applicable particularly to that type of vending pump in which the pump-rod has fixed thereto a 15 rack-bar that is actuated by a gear and crank mechanism. In this type of pump it is the intent that upon each cycle of its action a definite unit quantity of liquid will be moved through and discharged from it, 20 and generally adjustment means are provided in pumps of this class for limiting the stroke of the plunger exactly so that the intended unit quantity of liquid will be discharged upon the complete operation of the 25 pump, no more and no less.

The object of the present invention is to afford a device that when applied to a dispensing pump will accurately register each and every discharge stroke, and each and 30 every fractional portion of the discharge strokes in order to prevent fraudulence upon the part of the operator. The invention herein set forth is devised with the purpose of registering the progression at all stages 35 of the action of the pump which results in discharge of fluid therethrough.

And a further object of the invention is to provide means for adjusting the registering apparatus relative to the pumping 40 mechanism so as to compensate for any differences in the extent of the movement of the latter that may occur in any adjustments made in the stroke of the pump to secure an accurate quantitative discharge therefrom.

The objects of the invention are accomplished by the construction illustrated in the accompanying drawings in which:—

Figure 1 is an end view of the counting apparatus showing its connection with the 50 rack-bar of a pump;

Fig. 2 is a projected view of Fig. 1 show-

ing a portion in section on the line 1— and another portion on the line 2—;

Fig. 3 is an end view of the gear casing showing the same and some of the interior 55 parts cut away;

Fig. 4 is a diagram showing the relative positions of the axial centers of the rotating mechanism in one position of the adjustable housing;

Fig. 5 is a similar diagram of the same in another position;

Fig. 6 is also a similar diagram indicating said centers meeting at a common point;

Fig. 7 is an end elevation in section on the 65 line 3—4 of Fig. 8;

Fig. 8 is a sectional view of Fig. 1 on the line 1—2 thereof; and

Fig. 9 is an end view of one of the clutch wheels showing the spring pressed ratchet 70 balls for same in connection therewith.

Similar characters of reference indicate corresponding parts throughout the several views and referring now to the same:

The invention consists of a construction 75 comprised of a cylindrical housing (5) having an integral head (6) at one end thereof and which is closed at its opposite end by a circular plate (7) that is secured in place by means of bolts (8), the latter 80 extending through the integral head and plate. The bolts used are square adjacent their heads and fit snugly through the head (6) so as not to turn therein. Castled nuts (9) on the outer ends of the bolts secure the 85 plate (7) against the adjacent end of the housing (5). Slots (10) in the plate (7) through which the bolts (8) pass are so formed as to admit of the plate being adjustably turned upon its axis which is in 90 line with the center of the housing. Attached to the outer face of the plate (7) is a counter (11) of the well known type having a series of numeral wheels (12) adapted to indicate numerically the cycles 95 of action of the apparatus with which it is attached. The stem (13) of the counter extends through the plate (7) into the housing and has fixed thereon a double clutch-wheel (14). The clutch-wheel has an outer 100 series of recesses (15) and a similar inner series of recesses (16), and in each series of

5 recesses are arranged a corresponding series of ratchet-balls (15') and (16') respectively. Extending around the inner portion of the clutch-wheel (14) is a clutch-sleeve (17), and adjacent thereto extending around the outer portion of the clutch-wheel is another clutch-sleeve (18), the former sleeving having a projecting slotted lug (19) and the latter having a similar slotted lug (20).
 10 A series of compression springs (21) is arranged within the clutch-wheel for each series of balls and tend to press the respective balls against the corresponding clutch-sleeves so that as the sleeve (18) is turned
 15 over toward the left hand the clutch-wheel will be moved accordingly because of the action of the spring pressed balls (15') in the recesses (15) against the inner face of the sleeve. And, when the sleeve (18) is
 20 revolved toward the right hand, the balls (15') bearing against the inner surface of the sleeve (18) will be pressed against the corresponding springs so that the sleeve may move in that direction without binding.
 25 During the latter movement of the sleeve (18) the clutch-wheel (14) is held from retraction by means of the spring pressed balls (16') in the recesses (16) that bear against the inner face of the clutch-sleeve
 30 (17), there being an anchor-screw (22) that extends from the plate (7) into the slotted lug (19) to prevent movement of the sleeve. Thus, it will be understood that as the outer sleeve (18) is moved, in one direction the
 35 stem (13) of the counter will be likewise moved and as the said sleeve is moved in the opposite direction the stem will be prevented from likewise moving. In this manner the stem of the counter is progressed in one
 40 direction only accordingly as the actuating sleeve (18) is moved over toward the left hand. The action of the springs against the balls in the recesses against the inner faces of the sleeves renders the clutching
 45 action extremely delicate, the clutch-wheel being progressed accordingly with the slightest driving movement of the outer sleeve and being also held from retraction by the balls within the inner sleeve when
 50 the movement of the outer sleeve is reversed. The result of this action is that the stem (13) of the counter is progressed intermittently in one direction only and the numeral wheels actuated thereby are pro-
 55 gressed accordingly. The stem (13) of the counter extends through the plate (7) at a point eccentric of the center upon which the plate is adjustably turned, and therefore as said plate is adjustably turned the
 60 axial center of the stem (13) is moved along the arc (23) accordingly.

It is the intention to actuate the driving clutch-sleeve (18) accordingly as the rack-bar (24) of the pump is moved by means

of mechanism that will admit of no lost motion through the transmission of movement, so that the numeral wheels of the counter will become progressed with minute accuracy and thus register exactly the discharge of the pump. 70

It is a well known fact that in dispensing pumps of the class to which this invention is applied, the stroke of the pump of necessity requires delicate adjustment in order that the quantity of discharge at each 75 of its cycles of action will be of a definite unit of measurement, such for example, one gallon. Well known means are ordinarily applied for the purpose and are not herein illustrated, it being deemed sufficient in 80 showing the application of the invention by illustrating a portion of a rack-bar (24) that is customarily attached to the pump-rod and moves therewith so that its reciprocal movements are of the same length as the stroke 85 of the pump. It is essential to this invention that the stem (13) of the counter shall be moved with accuracy proportionately as the rack-bar of the pump is moved in the discharge stroke of the pump, and owing to 90 the adjustable variations that are occasioned in the length of the stroke of the rack-bar above referred to it is essential also that a compensating adjustment be provided for the mechanism (hereinafter described) that 95 transmits motion from the rack-bar to the driving clutch-sleeve (18) of the counter mechanism in order that the latter will become actuated accurately in proportion to the amount of liquid discharged by the 100 pump. With this object in view a transmitting mechanism has been provided and applied to the rack-bar and driving clutch-sleeve (18) that is effective in transmitting the required action without lost motion, and 105 which admits of compensating adjustments as the length of stroke of the pump is adjustably varied.

The transmitting mechanism referred to is comprised of two parts: An intermediate gear (25) which is mounted upon a stud (26) that extends from the head (6) into the housing (5), the axial center of the stud being in line with the arc (23) in which the stem (13) of the counter moves as the plate 110 (7) is adjustably turned; the other portion of the transmitting mechanism consists of a gearing engaging the intermediate gear (25) and rack-bar (24) and being so constructed as to eliminate "lost motion" in its 115 transmission of action between the rack-bar and the intermediate gear. This gearing is comprised of a driving gear (27) that has fixed relation with a hub (28), there being a key (29) for securing the gear and hub relatively in position, and a follower, (30) consisting of a gear that is similar to the gear (27) and that is loosely mounted upon the 120

hub (28). (31) is a spring, one end (32) of which extends through one tooth of the driving gear (27), and the other end (33) of which extends through one tooth of the following (30); a shaft (34) rigidly fixed in the hub (28) forms the axis thereof, and a driving pinion (35) is mounted thereon adjacent the inner end of the hub, and a pin (36) extending into the hub and pinion secures the hub and pinion so as to rotate together; a follower pinion (37) is loosely mounted upon the shaft (34) immediately adjacent the driving pinion (35); and a torsional spring (38) having one of its ends (39) fixed 10 to the shaft and its other end (40) engaging the follower pinion, tends to hold the latter pinion with its teeth bearing against the teeth of the intermediate gear (25) with which it is engaged, in the opposite direction 15 to that of the driving pinion (35) which is also in mesh with the intermediate gear. A projection (41) extending outwardly from the head (6) and having a bushing (42) therein serves as a bearing for the hub (28), 20 and the hub is held within its bearing by means of a groove (43), made in the hub, and a pin (44) that extends through the projection and groove, the groove being annular rotation of the hub is not hindered but 25 endwise movement thereof is prevented. As the gear (27) is actuated by the rack-bar (24) the faces (45) of its teeth bear against the faces (46) of the rack-bar and the faces (47) of the follower gear (30), owing to the 30 action of the spring (31), bear against the faces (48) of the rack-bar, thus at all times the teeth (45) of the driving gear (27) are constantly held against the corresponding faces (46) of the rack-bar, and the hub (28) 35 to which the driving gear (27) is fixed is rotated with minute precision and without lost motion as the rack-bar is reciprocated. Likewise the driving pinion (36) and follower pinion (37) are held respectively 40 with their teeth against the opposite faces of the teeth of the intermediate gear (25) owing to the torsional action of the spring (38), and thus said gear is actuated with minute precision as the hub is revolved. A 45 wrist-pin (49) projects from the face of the intermediate gear (25) eccentric of its center and extends into the slotted lug (20) of the driving clutch-sleeve (18) so that as the intermediate gear is oscillated the clutching 50 sleeve is likewise moved and the counter accordingly actuated. By adjustably shifting the plate (7) that carries the counter and clutch mechanism, the stem (13) of the counter becomes accordingly shifted relative to 55 the stud (26) upon which the intermediate gear rotates, so that the consequent oscillations of the clutch-sleeve (18) are differential to more or less extent and the counter is progressed more or less accordingly. The 60 diagrams, (Figs. 4, 5 and 6) are made to 65 illustrate several of the relative positions of the centers of the counter stem, and stud upon which the intermediate gear rotates. In Fig. 6 the centers of the stem and stud are in alinement at the intersection of the 70 arc (23) and horizontal line (23'), and the center upon which the plate (7) is adjustably oscillated is at the intersection of the horizontal line (23') and the perpendicular line (23''). When in this position, the centers of the stem and stud being in alinement, the clutch-sleeve (18) becomes uniformly actuated with the intermediate gear; in Figs. 4 and 5 the center of the stud (26), 75 being stationary, remains at the intersection of the arc (23) and horizontal line (23'), while the center of the stem in Fig. 4 lies above the center of the stud at the intersection of the arc (23) and lines (23') drawn above, and in Fig. 5 the center of the stem is 80 at the intersection of the arc (23) and the lines (23'') beneath the intersection of the arc (23) and horizontal line (23'). Thus the axial center of the counter may be 85 adjustably shifted by turning the plate (7) as occasion may arise in order to compensate for any adjustable variations made in the stroke of the pump so that the consequent movement of the counter will correspond 90 precisely with the quantitative discharge of the pump. It is contemplated that the stem of the counter shall turn one-half revolution precisely upon each discharge stroke of the pump or complete upward movement of the 95 rack-bar. Therefore when the rack-bar has 100 been adjustably limited in the usual manner, so that the discharge of the pump is of the desired quantity unit of measurement, the plate (7) is adjustably shifted to a position such as will result in the proper progression 105 of the stem through the medium of the gearing and clutch-mechanism accordingly as the discharge stroke of the pump takes place. 110 The invention is comprised of the housing, the counter adjustably mounted in connection therewith, the clutch-mechanism that actuates the counter located in the housing, the intermediate gear also located within the housing and the gear mechanism having actuated relation with the rack-bar of the pump and driving relation with the intermediate gear. The housing is arranged in juxtaposition with the rack-bar of the pumping mechanism so that the driving gear (27) and its companion follower gear (30) engage in mesh with the rack-bar. It is the intention that the housing shall be stationary and may either comprise a part of the pump frame or be secured substantially to a 115 stationary part of the pump-frame, the latter not being illustrated. 120

What I claim is:—

1. In apparatus of the class described, in

- combination with a pumping means having a rack-bar by which the same is actuated, a counter having a stem for actuating the same, a clutch mechanism on the stem for actuating it in one direction and holding the same from retracting, and a rotatable gear mechanism actuated by the rack-bar of the pump and being adapted to drive the clutch mechanism.
- 10 2. In combination with a rack-bar-driven pumping mechanism, a counter, means to actuate the counter including a clutch mechanism and intermediate gear, a driving gear in actuated relation with the rack-bar of the pumping mechanism, a pinion rotatably movable with the driving gear and engaging in mesh with the intermediate gear; and means in operative relation with the driving gear and pinion for holding the teeth thereof constantly in close contact with the teeth of the rack-bar and intermediate gear respectively.
- 15 3. In combination with a rack-bar, a counting mechanism including means for progressing the same and also a gear, a driving gear in actuated relation with the rack-bar, and having means in connection therewith for actuating the former gear, and means for preventing back-lash between the rack-bar, driving gear and the former gear.
- 20 4. In combination with a rack-bar-driven pumping mechanism, a counter, a clutch mechanism for actuating the counter, a gear having driving relation with the clutch mechanism, the axis of the gear being normally in alignment with the axis of the clutch-mechanism, and means for adjustably shifting the axis of the clutch-mechanism relative to the axis of the intermediate gear, there being means in connection with the rack-bar of the pumping mechanism and said gear for the transmission of movement from the former to the latter.
- 25 5. In combination with a rack-bar-actuated pumping mechanism, a housing, a plate adapted to be adjustably mounted upon its axial center and secured to the housing, a counter supported by the plate and having a stem for actuating the same extending through the plate eccentric of the axial center thereof, a clutch mechanism on the stem for progressing the same rotatively and preventing the same from retraction, and a gear within the housing, the axial center of which is in line with the axis of the stem when the plate is in its initial position, said gear having a sliding connection with the clutch mechanism for actuating the same, there being means in connection with the rack-bar of the pumping mechanism and said gear for the transmission of movement from the former to the latter.
- 30 6. In combination with a rack-bar-actuated pumping mechanism, a counter, a ratchet mechanism in connection with the counter for progressing the same and preventing the same from retraction, a gear having actuating relation with the clutch-mechanism, a driving gear actuated by the rack-bar, a loosely mounted follower gear 70 also in mesh with the rack-bar, a spring engaging the driving gear and follower tending to hold the teeth of said gears oppositely in contact with the opposite faces of the teeth of the rack-bar respectively, a pinion rotatively movable with the driving gear and engaging the intermediate gear, a loose pinion mounted to rotate upon an axial center common with the former pinion, and a torsional spring engaging the loose pinion and adapted to cause the teeth of the loose pinion to bear against the teeth of the intermediate gear oppositely to that of the former pinion.
- 35 7. In combination with a rack-bar-driven pumping mechanism, a counter, means for actuating the counter including a clutch mechanism and intermediate gear, a shaft, a driving gear actuated by the rack-bar adapted to rotate the shaft, a follower gear loosely mounted upon an axis common with the driving gear, a spring in connection with the driving gear and follower tending to hold the teeth of said gear and follower in contact with the opposite faces of the teeth of the rack-bar respectively, two pinions mounted upon the shaft and meshing with the intermediate gear, one of which is adapted to move with the driving gear, and a torsional spring fixed at one end to the shaft 90 and having engagement at its other end with the other of said pinions and tending to hold the same so that its teeth bear oppositely against the teeth of the intermediate gear to that of the former pinion.
- 40 8. In combination with a rack-bar actuated pumping mechanism, a counter having a driving stem and adjustably mounted, a clutch-mechanism for actuating the counter, an intermediate gear adapted to rotate upon a fixed center and having driving relation with the clutch-mechanism, a driving gear actuated by the rack-bar, a pinion movable with the driving gear and engaging the intermediate gear, means engaging the driving gear and rack-bar adapted to hold the teeth of the former constantly in contact with the corresponding faces of the teeth of the rack-bar, and means for preventing lost motion between the pinion and intermediate gear.
- 45 9. In combination, a toothed driving member, a toothed driven member, a rotatable hub, a gear rigidly fixed on the hub and meshing with the driving member, another gear loosely mounted upon the hub also meshing with the driving member, a take-up spring in connection with said gears, a pin-

ion in fixed relation with the hub and engaged with the driven member, a second pinion loosely mounted in alinement with the former pinion and also engaged with the driven member, and a take-up spring for the latter pinion.

In testimony whereof I affix my signature in presence of two witnesses.
